UNITED STATES PATENT OFFICE.

MAX RACHLIN, OF NEW YORK, N. Y., ASSIGNOR TO PATENTED METALWARE CORPORATION, OF BROOKLYN, NEW YORK, A CORPORATION OF NEW YORK.

GUTTER-HANGER.

1,392,966.

Specification of Letters Patent.

Patented Oct. 11, 1921.

Application filed April 29, 1920. Serial No. 377,698.

To all whom it may concern:

Be it known that I, MAX RACHLIN, a citizen of Russia, and a resident of the city of New York, in the county of Kings and 5 State of New York, have invented certain new and useful Improvements in Gutter-Hangers, of which the following is a specification.

The present invention relates to supports 10 or brackets for supporting roof-gutters.

The invention pertains more particularly to extensible roof-gutter brackets of the type described in my application for U. S. Letters Patent, Serial No. 353,971, filed Jan. 15 26, 1920. In this application a roof-gutter bracket is described, comprising a bar adapted to be placed transversely across the upper open edge of a roof-gutter, said bar being composed of two longitudinally adjustable sections, having their ends in overlapping relation and provided with apertures, in combination with a fastening element extending through alined apertures in the overlapping ends of said sections, said 20 fastening element serving at the same time to attach to the bar an arm, which is adapted to be secured to the roof of the building.

The main object of the present invention is to so construct the sections of the said 30 bar that a rigid construction is obtained, for properly supporting the gutter.

Another object is to produce a gutter support or bracket of the type mentioned, which is simple in construction, durable, and one 35 which is capable of manufacture on a commercial scale, that is to say one which is not so difficult to make as to be beyond the reasonable cost of such a contrivance.

With these and other objects in view, 40 which will more fully appear as the nature of the invention is better understood, the same consists in the combination, arrangement and construction of parts hereinafter described, pointed out in the appended 45 claims and illustrated in the accompanying drawings, it being understood that many changes may be made in the size and proportion of the several parts and details of construction within the scope of the appended 50 claims, without departing from the spirit or sacrificing any of the advantages of the invention.

One of the many possible embodiments of the invention is illustrated in the accompanying drawings, in which:—

Figure 1 is a side elevation, partly in section, of a bracket constructed in accordance with the present invention, showing the same in position upon a roof and gutter; Fig. 2 is a top plan view of the bar portion 60 of the bracket; Fig. 3 is a longitudinal section taken through the bar, on a larger scale; Fig. 4 is a section taken on line 4—4 of Fig. 3; and Fig. 5 is a perspective view of one end of the said bar.

In the drawings the numeral 10 indicates a bar or member, which is adapted to be placed transversely across the upper open end of a roof-gutter. This bar is made up of two sections, denoted by the numerals 70 11 and 12. The section 12 is of inverted U-shape in cross-section, and adapted to telescope into the section 11, the latter being also of inverted U-shape in cross-section, the free ends 13 of its parallel legs 14 being 75 bent inwardly toward each other, as clearly appears from Fig. 4 of the drawings. These inwardly bent portions serve as a support for the bar section 12, the legs 15 of the section 12 abutting against the said 80 inwardly bent portions throughout their telescoped lengths. The sections 11 and 12 are provided adjacent their meeting inner ends with longitudinal rows of apertures 16 and 17, respectively, and through registering 85 apertures of the two rows is adapted to be extended a fastening element, for instance, a screw bolt 18, to hold the two sections in adjusted position. This screw serves at the same time to attach the bar 10 to an upwardly extending arm 19, which is secured by nails 20, or otherwise, to the roof 21, from which the rain water is to be carried off.

The outer or free end of the bar section 95 11 is hook-shaped, as shown at 22, its open portion, being disposed downwardly and adapted to receive the outer beaded edge 23 of the gutter 24, the beaded edge being inserted within the hook, and the latter then 100 bent so as to engage and be partly closed around the said edge. If desired, some fastening element may be extended through an aperture 25 in the hook-shaped portion

22 of the bar section 11, said fastening element being driven into the beaded portion of the gutter.

The outer or free end of the bar section 12 is flattened and bent upwardly as shown at 26, and thence downwardly upon itself as indicated at 27. The portions 26 and 27 are provided with apertures 28 and 29, respectively, which are adapted to aline with each other when said portions 26 and 27 are bent so as to lie in parallel relation, in which they embrace that upper edge of the gutter which is disposed opposite to the beaded edge 23 thereof. A nail 30, or other suitable element, is driven through the apertures 28 and 29 and through the adjacent portion of the wall of the gutter, said nail being driven into the wall 31 of the structure, upon which the gutter is to be positioned.

The free end of the portion 27 of the bar section 12, is provided with a prong 32, which is adapted to be driven through the wall of the gutter, so as to form additional means for securing the bracket thereto.

The bar 10 is preferably made of sheet metal, and, by reason of its sections being longitudinally adjustable in relation to each other, the supporting bracket may be made 30 to fit roof-gutters of various widths. In adjusting the bracket, it is only necessary to remove the bolt 18 and to shift the sections 11 and 12 into proper position, and then insert the bolt so as to clamp them 35 together. Inasmuch as the bar sections are U-shaped in cross-section, a rigid structure will be obtained. Furthermore, since the bar section 12 is abutting throughout its telescoped length against the inwardly bent 40 ends 13 of the legs of the section 11, rela-

tive movement between the inner ends of the bar in a vertical plane is effectively prevented.

What I claim is:—

1. A gutter hanger comprising a bar 45 adapted to be placed transversely across the upper open end of a gutter and terminally secured to the upper edge portions thereof said bar being formed of an inner and an outer section slidably secured together, the 50 outer section having inwardly projecting flanges for bodily supporting the inner section and means for securing the sections in desired adjusted position.

2. A gutter hanger comprising a bar 55 terminally secured to the upper edge portions of a gutter, said bar being formed in cross section of inverted substantially U-shaped inner and outer members slidably secured together, said outer member having 60 inwardly directed flanges for slidably supporting the inner section within the outer section and means for securing the sections in desired adjusted position.

3. A gutter hanger comprising a section 65 sheet metal bar telescopically secured together, the outer end of one section being formed of a bendable hooked portion to be crimped over the beaded end of the gutter and the outer end of the other section being 70 upwardly bent at right angles to the section thence downwardly and terminating in a sharpened prong for penetrating the opposite upper edge of the gutter when the end of the last mentioned section is pinched together.

Signed at New York, in the county of New York and State of New York this 10th day of March A. D. 1920.

MAX RACHLIN.
